[57] CLAIM

The ornamental design for a packaging container for roller blinds, as shown and described.

DESCRIPTION

FIG. 1 is a front elevational view of a packaging container for roller blinds showing my new design, the rear being a mirror image thereof;

FIG. 2 is a side elevational view;

FIG. 3 is an enlarged perspective view with a portion of the center broken away for convenience of illustration;

FIG. 4 is an exploded perspective view of the hook end cap elements;

FIG. 5 is a side elevational view of the hook;

FIG. 6 is an enlarged fragmentary view of the lower part of the hook; and

FIG. 7 is an enlarged front elevational view of the hook.

FIG: 7.

FIG: 5.

FIG: 6.

FIG: 4.
